1

This invention relates to a mixer circuit-arrangement for centimetre waves, in which use is made of a so-called travelling wave amplifying tube. A known construction of such a tube used for the amplification of centimetre waves comprises a system for producing an electron beam, and in addition a helical conductor along which the waves to be amplified propagate and which is arranged with respect to the said system in such manner that the electrons of the beam move approximately axially with the helix. The waves to be amplified are fed to that end of the helix which is nearest to the electron beam, and the winding pitch of the helix and/or the diameter; the turns and the voltages used for producing the electron-beam are chosen to be such that the speed of propagation of the waves measured along the axis of the helix is slightly lower than the mean velocity of the electrons of the beam. Under these conditions the electrons give off energy to the waves, so that these amplified waves can be taken from the end of the helix remote from the source of electrons.

The invention is based on the recognition that a tube operating on this principle may be used with a given modification, as a mixer tube for centimetre waves.

For this purpose the oscillations to be mixed and an auxiliary oscillation are fed, according to the invention, to the helical conductor in such manner as to produce travelling waves along the helix (helices), these waves moving in the same sense, and preferably at the same velocity or at a slightly lower velocity than the electrons. After having traversed the helix or helices the electrons are separated according to their velocity with the aid of a suitable electrode system from which at the same time the intermediate frequency oscillation is taken.

The actual occurrence of an intermediate frequency oscillation in the output circuit is due to the fact that on traversing the helix or helices the electrons of the beam reach different velocities owing to the traversing waves, so that after velocity detection in the said electrode-system an oscillation of difference-frequency results in the output circuit.

The oscillation to be mixed and the auxiliary oscillation may jointly be supplied to the end of the same helix nearest to the source of electrons; in this case the tube need only comprise a single helical conductor. As an alternative, two or more helices may be provided and the oscillation to be mixed and the auxiliary oscillation may be fed to different helices. In order

2

to avoid radiation of oscillations of the frequency of the auxiliary oscillation by avoiding an aerial connected, if any, to the input circuit, the helix to which the oscillation to be mixed is supplied is preferably located nearer to the source of electrons than the helix to which the auxiliary oscillations are fed. If desired, the auxiliary oscillation may be produced in the tube itself.

In the drawing,

10 Figure 1 is a schematic diagram of a first preferred embodiment of the invention;

Fig. 2 is a curve explanatory of the operation of Fig. 1; and

15 Fig. 3 is a schematic diagram of a second embodiment of the invention.

In order that the invention may be more clearly understood and readily carried into effect, it will now be described more fully with reference to the accompanying drawing, in which one em-

20 bodiment comprising two helices is represented by way of example in Fig. 1. The tube 1 represented therein comprises a system 2 for producing an electron-beam, two helices 10 and 11 ar-

25 ranged coaxially with the tube and in line with one another and a system for velocity detection which consists of a cylindrical electrode 3 and a collecting electrode 4 arranged slightly obliquely relatively to the axis of the tube. In this case it is advantageous to apply to the cylindrical electrode 3 a voltage slightly differing from earth potential and to apply a slightly positive voltage to the electrode 4. For the sake of simplicity the sources of potential required for this purpose are not represented. The end of the helix

30 10 located on the side of the source of electrons is earthed through an impedance 5 at which the input oscillations occurring at the terminals 12 appear. The other end of this helix is earthed through an impedance 6, the value of which substantially corresponds with the surge impedance of the helix 10, so that travelling waves moving from the left to the right occur therein. The source 7 for the auxiliary oscillation is connected in between the left-hand end of the helix 11 and earth, whilst the other end of this helix is like- 35 wise earthed through an impedance 8, the value of which is adapted to the helix 11, so that in the helix 11 travelling waves of the auxiliary frequency occur which move from the left to the right. The collecting electrode 4 is earthed through the circuit 9 tuned to the intermediate-frequency oscillations. As indicated by a dotted line the electron stream moves approximately along the axis of the helices 10 and 11 and the

40 45 cylinder 3.

50 55

The operation of the circuit-arrangement may be described with reference to Fig. 2. This figure shows a curve representing the relation between the current I_4 flowing from the electrode 4 to the output circuit and the velocity of the electrons of the beam. According as this velocity is lower more electrons of the beam will be attracted by the cylinder 3, so that a smaller part will flow to the electrode 4. Since the relation between the output current and the electron velocity is not linear, the electrode system 3, 4 will operate as a velocity detector. Owing to the helices 10 and 11 the successive electrons of the beam reach different velocities in accordance with the intensity of the waves on the helices 10 and 11, so that in the output circuit 9 an oscillation may occur, the frequency of which is equal to the difference between the frequencies of the oscillation to be mixed and the auxiliary oscillation.

Fig. 3 schematically illustrates a mixing circuit wherein the traveling wave tube includes but a single section helix 13, the local oscillations 7 and the input oscillations both being applied to the terminus of the helix adjacent the electron gun.

What we claim is:

1. Apparatus for mixing first and second high-frequency oscillations of different frequency to produce intermediate-frequency oscillations comprising a traveling-wave electron beam tube including a helical conductor for guiding oscillations, an electron beam source adjacent one end of said conductor and a collector electrode adjacent the other end of said conductor, said source being arranged to direct an electron beam along the axis of said helical conductor toward said collector electrode with a velocity which at any point thereon exceeds that of the traveling wave of oscillations as measured along said axis, means to apply said first and second oscillations to said helical conductor to produce traveling waves thereon which advance in the same direction as said electron beam, and means to derive the intermediate-frequency oscillations from said collector electrode.

2. Apparatus for mixing first and second high-frequency oscillations of different frequency to produce intermediate-frequency oscillations comprising a traveling-wave electron beam tube including a helical conductor for guiding oscillations, an electron beam gun adjacent one end of said conductor and a collector electrode adjacent the other end of said conductor, said gun being arranged to direct an electron beam along the axis of said helical conductor towards said collector electrode with a velocity which at any point thereon exceeds that of the traveling wave of oscillations as measured along said axis, input circuit means to apply said first and second oscillations to said helical conductor at said one end thereof to produce a traveling wave thereon which advances in the same direction as said electron beam, an impedance connected to said other end of said conductor and having a value matching the surge impedance of said conductor, and output circuit means to derive the intermediate-frequency oscillations from said collector electrode.

3. Apparatus for mixing first and second high-frequency oscillations of different frequency to produce intermediate-frequency oscillations comprising a traveling wave electron beam tube including a helical conductor for guiding oscillations, an electron beam gun adjacent one end of

said conductor, a collector electrode adjacent the other end of said conductor and a retarding tubular electrode interposed between said collector electrode and the other end of said tube, said gun being arranged to direct an electron beam along the axis of said helical conductor through said tubular electrode towards said collector electrode with a velocity which at any point thereon exceeds that of the traveling wave of the oscillations as measured along said axis, input circuit means to apply said first and second oscillations to said helical conductor at said one end thereof to produce a traveling wave thereon which advances in the same direction as said electron beam, an impedance connected to said other end of said conductor and having a value matching the impedance of said conductor, and output circuit means to derive the intermediate-frequency oscillations from said collector electrode, said last named means including a resonant circuit connected between the collector electrode and said tubular electrode and tuned to said intermediate frequency.

4. An apparatus, as set forth in claim 3, further including means to bias said collector electrode positively with respect to said retarding electrode.

5. An apparatus, as set forth in claim 3, wherein said collector electrode is disposed obliquely relative to the axis of said beam.

6. Apparatus for mixing first and second high-frequency oscillations of different frequency to produce intermediate-frequency oscillations comprising a traveling-wave electron beam tube including a helical conductor for guiding oscillations, said helical conductor being constituted by separate first and second sections each having end terminals, an electron beam gun adjacent one end of said helical conductor, a collector electrode adjacent the other end of said conductor, said gun being arranged to direct an electron beam along the axis of said helical conductor successively through the first and second sections thereof toward said collector electrode with a velocity which at any point thereon exceeds that of the traveling wave of oscillations as measured along said axis, means to apply said first oscillations to the terminus of said first section adjacent said gun, means to apply said second oscillations to the terminus of said second section adjacent said gun, and means to derive the intermediate-frequency oscillations from said collector electrode.

7. Apparatus for mixing first and second high-frequency oscillations of different frequency to produce intermediate-frequency oscillations comprising a traveling wave electron beam tube including a helical conductor for guiding oscillations, said helical conductor being constituted by separate first and second sections, an electron beam gun adjacent one end of said conductor, a collector electrode adjacent the other end of said conductor and a retarding tubular electrode interposed between said collector electrode and said other end of said conductor, said gun being arranged to direct an electron beam along the axis of said helical conductor successively through the first and second sections thereof toward said collector electrode with a velocity which at any point thereon exceeds that of the traveling wave of oscillations as measured along said axis, first input circuit means to apply said first oscillations to the terminus of said first section adjacent said gun, second input circuit means to apply said second oscillations to the terminus of said second

section adjacent said gun, and output circuit means to derive the intermediate-frequency oscillations from said collector electrode, said last named means including a resonant circuit connected between the collector electrode and said tubular electrode and tuned to said intermediate frequency.

8. Apparatus for mixing first and second high-frequency oscillations to produce intermediate-frequency oscillations, the frequency of said first oscillations being high relative to said second oscillations, said apparatus comprising a traveling wave electron beam including a helical conductor for guiding oscillations, said helical conductor being constituted by separate first and second sections, an electron beam gun adjacent one end of said conductor, a collector electrode adjacent the other end of said conductor and a retarding tubular electrode interposed between said collector electrode and said other end of said conductor, said gun being arranged to direct an electron beam along the axis of said helical conductor successively through the first and second sections thereof toward said collector electrode with a velocity which at any point thereon exceeds that of the traveling wave of oscillations as measured along said axis, first input circuit means to apply said first oscillations to the terminus of said first section adjacent said gun, a first matching impedance connected to the other terminus of said first section, second input circuit means to apply said second oscillations to the terminus of said second section adjacent said gun, a second matching impedance connected to the other terminus of said second section, and means to de-

rive the intermediate-frequency oscillations from said collector electrode, said last named means including a resonant circuit tuned to the frequency of said intermediate frequency oscillations and connected between said retarding and collector electrodes.

9. Mixing apparatus, as set forth in claim 8, wherein said collector electrode is disposed obliquely with respect to the axis of said beam and further including means to apply a constant voltage to said collector electrode which is positive with respect to said retarding electrode.
